UNITED STATES PATENT OFFICE.

FRANK F. BURTON, OF NEW HAVEN, CONNECTICUT, ASSIGNOR TO WINCHESTER REPEATING ARMS CO., OF NEW HAVEN, CONNECTICUT, A CORPORATION.

EXTRACTOR FOR FIREARMS.

SPECIFICATION forming part of Letters Patent No. 790,615, dated May 23, 1905.

Application filed December 6, 1904. Serial No. 235,731.

To all whom it may concern:

Be it known that I, FRANK F. BURTON, a citizen of the United States, residing at New Haven, in the county of New Haven and State 5 of Connecticut, have invented a new and useful Improvement in Extractors for Firearms; and I do hereby declare the following, when taken in connection with the accompanying drawings and the figures of reference marked 10 thereon, to be a full, clear, and exact description of the same, and which said drawings constitute part of this specification, and represent, in—

Figure 1, a broken view, partly in right-hand side elevation and partly in vertical longitudinal section, of a gun constructed in accordance with my invention, showing the bolt closed and locked and the extractor in readiness to engage with the spent shell upon the 15 initial movement of the bolt in starting rearward; Fig. 2, a similar view with the bolt unlocked and drawn back into position for picking up and pulling back the extractor, the forward end of which has been released by the bolt, 20 and thus permitted to engage with the spent shell; Fig. 3, a similar view with the bolt and extractor drawn to the limit of their rearward positions, the extractor being shown in the position which it takes after the ejection of 25 the spent shell; Fig. 4, a similar view with the bolt pushed forward to the point at which its beveled forward end engages with the depressing-cam of the extractor for depressing the same, so that the releasing-finger thereof 30 will clear the releasing-shoulder formed in the gun-barrel at a point directly below the cartridge-chamber therein; Fig. 5, a detached reverse plan view of the bolt; Fig. 6, a detached view, in side elevation, of the extractor. 35

My invention relates to an improvement in firearms, with particular reference to extractors therefor, the object being to provide simple, durable, and effective means for extracting and ejecting the spent shells.

With these ends in view my invention consists in certain details of construction and

combinations of parts, as will be hereinafter described, and pointed out in the claims.

In carrying out my invention as herein shown I employ a longitudinally-movable extractor 2, slightly bowed from end to end, so as to form a spring, and located in a long slot 3, formed in the center of the lower face of the integral bolt-receiving barrel extension 4 of 55 the gun-barrel 5. Upon the upper face of its rear end the extractor is formed with an operating-lug 6, entering a longitudinal slot 7, formed in the center of the lower face of the longitudinally-movable and rotary bolt 8. 60 The length of this slot 7 will be determined by the length of the shell 9 and the extent to which the bolt moves back and forth. Near its forward end the extractor is formed with an extracting-hook 10, adapted to enter a 65 notch 11, formed beneath the cartridge-receiving chamber 5^a in the barrel 5 to permit the said hook 10 to engage with the forward face of the flange or rim of the shell.

The extreme forward end of the extractor 70 consists of a releasing-finger 12, entering when the gun is closed a notch 13 in the barrel 5 and when the gun is open a notch 14 therein, these notches being separated by a shoulder 15, which for convenience I shall call a “releasing-shoulder,” for the reason that when the gun is opened the finger 12 drops off the shoulder 15 from the notch 13 into the notch 14 and allows the forward end of the extractor 75 to spring upward for the ejection of the 80 spent shell, which at this time has been fully extracted from the chamber 5^a in the barrel 5. To the rear of the hook 10 the extractor is formed with a depressing-cam 16, which is engaged by an annular bevel 17, formed at 85 the forward end of the bolt 8.

It will be seen by reference to Fig. 1 that when the bolt is moved into its closed and locked position its bevel 17, engaging with the cam 16, depresses the forward end of the 90 extractor, which is thus placed under spring tension, with its nose 10 located slightly below and slightly forward of the rim or flange of the cartridge 9. Now when the bolt is un-

locked and started, in being drawn back it moves away from the forward end of the extractor and permits the same to rise sufficiently for the engagement of its hook 10 with the flange of the spent shell; but the extractor is not itself moved longitudinally. When, however, the bolt has been drawn back to the extent shown in Fig. 2, the forward end wall 7^a of the slot 7 in the bolt engages with the forward edge of the operating-lug 6 of the extractor, causing the bolt to "pick up," so to speak, the extractor, which from that time it pulls rearward, and so extracts the spent shell 9 from the chamber 5^a. During this rearward movement of the extractor with the bolt the releasing-finger 12 of the extractor rides over the bottom of the notch 13. By the time the said finger 12 has reached the releasing-shoulder 15 the spent shell has been fully extracted and is therefore free to be snapped or ejected from the gun under the impulse caused by the recovery of the spring-extractor when its finger 12 drops off the shoulder 15 from the extra tension under which it was placed when the bolt was closed. After the end of the finger has snapped over the shoulder 15 the extractor will take the position in front, so to speak, of the bolt, as shown in Fig. 3. Now when the bolt is again closed the bevel 17 at its forward end impinges against the depressing-cam 16 of the extractor and forces the same downward, so that the forward end of its releasing-finger 12 is pushed below the shoulder 15, which must be cleared by the said finger in order to permit the extractor to be shoved forward by the bolt into its closed position.

I would have it understood that my improved extractor may be embodied in guns differing in construction from that herein shown and described. On that account it seems unnecessary to describe in detail the construction of the gun shown. It may be said, however, that the bolt is furnished with a firing-pin 18, having a firing-nose 19, with a firing-pin spring 20, a stop-pin 21, an operating button or finger-piece 22, and with a sear-notch 23, which latter coacts with a sear 24, hung on a pin 25 and operated by a trigger 26. The bolt has a transversely-arranged operating-handle 27 and is formed with a cut 28 for the clearance of the operating-lug 6 of the extractor and with a cut 29, through which the sear reaches the sear-notch 23 in the firing-pin. The bolt-receiving barrel extension 4 is formed with a chamber 30 for the reception

of the bolt and with a cartridge-receiving and cartridge-ejecting opening 31. The sear 24 is controlled by a sear-spring 32, acting through a small plunger 33 in the well-known manner.

It is apparent that in applying my improved extractor to different guns it may be necessary to change it in some respects, as well as to adapt them to receive and operate it. I would therefore have it understood that I do not limit myself to the exact construction shown and described herein; but hold myself at liberty to make such departures therefrom as fairly fall within the spirit and scope of my invention.

Having fully described my invention, what I claim as new, and desire to secure by Letters Patent, is—

1. As a new article of manufacture, a longitudinally-movable extractor for bolt-guns, the said extractor being provided at its rear end with an operating-lug, and at its forward end with an extracting-hook, a depressing-cam and a releasing-finger. 75
2. In a bolt-gun, the combination with a barrel formed with a cartridge-chamber and cut away below the same to form a releasing-shoulder, of a bolt, and a longitudinally-movable extractor located below the bolt, adapted at its rear end to be engaged by the bolt by means of which it is operated, and provided at its forward end with an extracting-hook, a depressing-cam which is engaged by the bolt, and a releasing-finger which rides off the said releasing-shoulder for the ejection of the spent shell. 80
3. In a bolt-gun, the combination with a barrel formed with a cartridge-chamber and with a releasing-shoulder located below the same, of a bolt having its forward end beveled and its rear end grooved, and a longitudinally-movable extractor formed at its rear end with an operating-lug entering the groove in the bolt, and at its forward end with a depressing-cam coacting with the bevel at the forward end of the bolt, with an extracting-hook and with a releasing-finger which drops off the said releasing-shoulder in the barrel for the ejection of the spent shell. 85

In testimony whereof I have signed this specification in the presence of two subscribing witnesses.

FRANK F. BURTON.
